UNITED STATES PATENT OFFICE.

HELEN MAR VAN ETEN, OF MORAVIA, NEW YORK.

STIFFENER FOR CORSETS.

SPECIFICATION forming part of Letters Patent No. 336,606, dated February 23, 1886.

Application filed November 10, 1883. Serial No. 111,472. (No model.)

To all whom it may concern:

Be it known that I, HELEN M. VAN ETEN, a citizen of the United States, residing at Moravia, in the county of Cayuga, and State of New York, have invented certain new and useful Improvements in Stiffening Fabrics; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention and is a plan view. Fig. 2 is a vertical section taken in the direction of the broken line *xx*.

This invention has relation to stiffening fabrics for corsets and other garments or wearing apparel, and is designed to take the place of cork, whalebone, tampico, coraline, canvas, hair-cloth, and other stiffening materials heretofore used, and has for its object to provide a stiff and at the same time a flexible material, sufficiently well ventilated by its nature to be cool in summer, composed of woven or braided sheets of East India phragmites, usually employed in the tea trade to incase tea-chests, in combination with textile fabric or analogous backing secured thereto by adhesive substance and then stitched or quilted to the phragmites, to form an article of manufacture to be used for stiffening in corsets and other apparel.

In preparing the sheets A of phragmites their usually unwholesome odor is removed by soaking the material in a weak solution of lime-water in about the proportion of one pound of lime to twelve sheets of the phragmites. The material is allowed to remain in the solution for about two hours, when it is removed and dried and pressed, and found to possess the requisite degree of flexibility without cracking or breaking, while at the same time it has the quality of stiffness desired.

After chemical preparation of the sheet of phragmites it is then faced with a flexible covering, B, of muslin or cloth, or, if desired, rubber or leather may be used, though for all practical purposes I prefer the textile fabric, as it is porous and consequently cooler in the summer season.

Whenever it is desired to have the stiffening material in combination with a perspiration-pad, to prevent soiling the outer garments, I use a facing of rubber in place of muslin. Of whatever material the facing is composed which is intended to cover one side of the prepared phragmites, the sheet B is first covered on one of its sides with glue, paste, cement, or other adhesive substance, and then laid upon the sheet of phragmites, and the two are securely pressed together until they have adhered and are dry, the facing B forming thereby a reinforcement to the phragmites, giving greater body and strength, and preventing the facing from leaving the body of phragmites, and from forming ridges and corrugations in the act of bending the body, as would be the case were the facing secured to the body only by sewing or quilting. The material thus prepared is quilted or stitched throughout its entire extent, as shown at C, to give it still greater solidity and firmness, and to prevent the strands of phragmites from separating in consequence of the movement of the body when the material is in long and continued use. The newly-prepared stiffening is then ready for use by being cut into shape for the particular part of the garment in which it is desired to use it. The pieces cut for use should be bound with braid or some other suitable material, D, to prevent raveling of the edges and to protect the fabric of the garment from wear and abrasion by the ends of the phragmites.

I am aware that palmetto-leaves have heretofore been plaited together and fabricstitched to the face thereof for use in corsets; but it is a well-known fact that palmetto-leaves possess but little elasticity and durability in comparison with the East India phragmites. The former when bent abruptly will either break or remain in its bent shape, while the phragmite may be folded over upon itself without injuring it. In fact, said two substances are entirely different species of vegetation, possessing different properties.

The substance which I have selected as the chief element of my invention has heretofore been considered unfit for any useful purposes except for wrappers around tea-chests. By my invention the phragmites, after they have served the aforesaid purpose, are converted into a new article of manufacture of great

utility and at a minimum cost. Furthermore, my invention is essentially different from prior devices of its class in that the body and its facing are firmly and uniformly united by adhesive material, which imparts the requisite stiffness to the article uniformly in all directions; hence I wish it distinctly understood that I do not consider the palmetto-leaves as the equivalent of the within-specified phragmites; 10 but

What I do claim as new, and desire to secure by Letters Patent, is—
As a new article of manufacture, a stiffening

material for corsets and other articles of wearing-apparel, consisting of a body formed of a 15 sheet of phragmites and a facing of flexible material secured thereto by an adhesive substance and the body and facing quilted or sewed together throughout its entire extent, substantially as and for the purpose set forth. 20

In testimony whereof I affix my signature in presence of two witnesses.

HELEN MAR VAN ETEN.
